UNITED STATES PATENT OFFICE.

RICHARD D. HANISH, OF COLUMBUS, OHIO.

POLISHING-DRUM.

1,071,519.

Specification of Letters Patent. Patented Aug. 26 1913.

Application filed January 15, 1913. Serial No. 742,247.

To all whom it may concern:

Be it known that I, RICHARD D. HANISH, a citizen of the United States, residing at Columbus, in the county of Franklin and State of Ohio, have invented certain new and useful Improvements in Polishing Drums, of which the following is a specification.

The present invention relates to improvements in polishing drums, and is particularly applicable for use in cleaning and polishing plane surfaces.

I have found the polishing drum of this invention especially effective in cleaning and renovating moving picture films, where a machine is used in which the film is supported on and passed over rolls, and while the film is being transferred from one roll to another, a plurality of these drums, properly supported, are used to clean and renovate the surface of the film. A machine of this character is illustrated and described in my copending application for patent Serial No. 709,544, filed July 15, 1912.

The invention consists in certain novel features of construction and combinations and arrangements of parts whereby the polishing cloth or fabric, in the form of a strip, is wrapped around the drum and its ends secured, to insure a smooth polishing surface for the drum.

In the accompanying drawings I have illustrated one complete example of the physical embodiment of my invention, and a modification thereof, showing the best modes I have so far devised for the practical application of the principles of the invention.

Figure 1 is a longitudinal vertical section of the drum per se. Fig. 2 is an end view of the drum, the polishing cloth and cushion being omitted, but ratchets of the winding apparatus illustrated. Fig. 3 is a transverse sectional view of a drum complete. Fig. 4 is an enlarged detail showing a catch for one of the winding devices. Fig. 5 is a vertical, central sectional view of Fig. 4, looking toward the left. Fig. 6 shows one of the winding devices in side elevation, parts being omitted. Fig. 7 is an enlarged detail view of one of the winding ratchets shown in Fig. 2. Fig. 8 illustrates a latch to be used in connection with the pawl and ratchet, and Fig. 9 illustrates a modified form of the invention.

In the preferred embodiment of my in-

vention I employ the drum 1 which is of suitable material, metal being illustrated, and formed with a continuous circumferential surface or perimeter 2 which is broken only by the longitudinal slot 3 which extends from near one end of the drum to the other.

The drum is furnished with a pair of bearing sleeves 4, 4, and spokes 5, between some of which are formed the webs 6, 6, to support necessary attachments.

The drum is wrapped or enveloped by a polishing cloth 7, in the form of a strip of suitable length and proper width, and between the cloth and the perimeter of the drum a cushioning member 8 is interposed. The ends of the cushion, which may be of felt or other suitable material, stop at the edges of the slot in the drum, and the edges or walls of the slot are provided with shields or guard strips 9, 9. These shields present a smooth surface over which the polishing cloth may be passed when adjusting the cloth to permanent or stationary position on the drum, and while I have illustrated the shields or wear plates as separate and independent elements, it will be understood that the edges or walls of the slot may themselves be fashioned to suitable form to take the place of the removable plates.

The ends of the cloth are secured to winding devices that are supported in the webs of the drum. These devices are identical in form, and it is thought the description of one device will suffice for both. The ends of the cloth are first secured about the bars 10 of the winding fork and these bars are integral with a head which comprises a bearing boss 11, a disk 12, and a nut portion 13, as seen most clearly in Fig. 6. The boss is adapted to turn in one of the perforated webs of the drum, and the fork extends longitudinally through the drum. The ends of the bars 10 are located in a perforated thimble 13', fitted in the web at the end of the drum opposite the fork head, and provided with an annular flange 14 contacting with the inner wall of the drum.

One of the bars 10 is longer than the other and projects beyond the thimble and also beyond the outer face of the drum web. A perforated cap plate 15, larger in diameter than the body of the thimble, and of the opening in the wall or web of the drum, is secured, as by screws 16 to the body of the thimble. This plate holds the thimble

from displacement toward the interior of the drum.

By means of the simple, spring held latch 17, pivoted at 18 to the plate, and adapted to engage the notch or recess 19 in the long bar of the fork, the winding device, or anchor for the end of the polishing cloth, is held in place.

It will be evident that when the end of the cloth is fixed to one of the fork bars, if the winding device is turned by applying a wrench to the nut head 13, the cloth will be wound upon the fork. The boss and thimble form bearings upon which the winding device turns in the perforated webs.

It will be understood of course that each end of the cloth is wound upon its own winding fork, and the cloth may be drawn taut over the cushioned drum by turning the winding devices in opposite directions.

To prevent reverse movement or unwinding of the cloth from the winding fork, I preferably provide the disk 12 with ratchet teeth, and pivot a toothed pawl 20 in operative relationship to the ratchet or disk, which is held in engagement with the ratchet teeth by a pull spring 21. To hold the pawl out of engagement with the teeth

I provide a detent 22 which is bent to U-shape and held in perforations in the wall of the drum by means of a flat spring 23. By moving the pawl over the hook end 24 of the detent it will be held out of engagement, and by pressure on the push bar 25 of the detent, it will be evident that the pawl is freed.

In Fig. 9 the forks 10' have both ends of the same cloth wound thereabout, and one of the winding devices is dispensed with.

By utilizing two winding devices, it will be readily understood that, when one portion of the polishing cloth becomes worn, by winding the cloth upon one fork and freeing it from the other, an entirely new

surface may be presented for use, without the annoyance of replacing a cloth that has been removed.

Claims:

1. The combination with a polishing cloth and drum, of a winding device comprising a headed fork rotatable in the drum, a thimble to receive the free ends of the fork, and means for holding said device in position in the drum.

2. The combination with a drum of a fork having a boss rotatable therein, a thimble fitted in a perforation in the drum and perforated to receive the free ends of the fork, means for holding the described device in the drum, and means for rotating said device.

3. A winding device comprising a fork having a bearing boss, and a nut, a thimble perforated to receive the free ends of the fork, a cap plate attached to said thimble, and means for securing said plate to a portion of the fork.

4. A winding device comprising a fork having bars of unequal length, a thimble perforated to receive the free ends of the bars, a perforated cap plate attached to the thimble through which the longer bar passes, and a spring catch on said plate to hold said bar.

5. The combination with a drum of a forked winding device having bars of unequal length, a flanged thimble perforated to receive the bars, a perforated cap plate attached to the thimble through which the longer bar passes, and means for locking the longer bar to the plate.

In testimony whereof he affixes his signature in presence of two witnesses.

RICHARD D. BANISH.
